(57) **CLAIM**

The ornamental design for a jacket, as shown and described.

DESCRIPTION

FIG. 1 is a front perspective view of a jacket;

FIG. 2 is a front elevation view thereof;

FIG. 3 is a rear elevation view thereof;

FIG. 4 is a right elevation view thereof;

FIG. 5 is a left elevation view thereof;

FIG. 6 is a top plan view thereof; and,

FIG. 7 is a front perspective view of an alternative embodiment of a jacket.

The broken lines showing a jacket are included for the purpose of illustrating environment and form no part of the claimed design.
